KEYING CONTROL METHOD AND SYSTEM

Richard A. Hilmerty, Baldwin, N. Y., assignor to
Press Wireless, Inc., Chicago, Ill., a corporation
of Delaware

Application December 12, 1940, Serial No. 369,812

14 Claims. (Cl. 178—66)

This invention relates to signalling systems and more especially to improved keying control arrangements for such systems.

A principal object is to provide a novel arrangement for producing substantially square-topped waves for use in telegraph signalling or similar systems.

Another principal object is to provide an improved keying control circuit which is particularly advantageous in automatic telegraph transmitters especially those of the Morse code type.

Heretofore it has been found necessary to employ polarized relays for converting the " fleeting contact" of the automatic Morse transmitting signal controller into "marking" or "spacing" impulses of symmetrical proportions. Since the armatures of conventional polarized relays have considerable mass, an appreciable time interval is required for the armature to complete its transit from the marking to the spacing contact and vice versa. This to a certain degree, represents a loss in signalling time.

Accordingly, it is another principal object of this invention to provide a keying control arrangement which is substantially inertialess so far as the beginning and ending of each signal interval is concerned, resulting in more nearly perfect square-topped signalling waves and a considerable increase in possible signal transmission speeds.

A feature of the invention relates to a keying controlling arrangement employing a novel combination of grid-controlled gas-discharge tube and grid-controlled vacuum tubes.

Another feature relates to an improved circuit arrangement for producing substantially square-topped envelopes of A. C. waves of magnified amplitude.

Another feature relates to an improved keying control circuit which can be controlled directly from the usual instantaneous contact controller or conventional automatic or tape-controlled telegraph transmitters, whereby intervening polarized relays or other similar electro-mechanical vibrators are avoided. As a result of this feature, the signalling wave shape and time can be improved because the armature transit time is substantially eliminated, and disturbances which very often arise from maladjustment, deterioration or sticking of the usual polarized relay contacts, are avoided.

A further feature relates to an improved keying control circuit employing a tube of the "thyatron" type.

A further feature relates to means for generating recurrent and substantially square-topped envelopes of A. C. waves at a rate determined substantially entirely by a local or distant timing oscillator, by employing a grid-controlled vacuum tube and a grid-controlled gas discharge tube in a balanced or quasi push-pull arrangement.

A still further feature relates to the novel organization, arrangement and relative interconnection of parts which constitute a more efficient keying control arrangement for telegraph signalling systems and the like.

Other features and advantages not specifically enumerated will be apparent after a consideration of the following detailed descriptions and the appended claims.

While the invention will be described herein in connection with one particular kind of signalling system, it will be understood that in certain of its aspects the invention is applicable to a wide variety of signalling systems or wave impulse control systems. In the drawing, which represents certain specific embodiments,

Fig. 1 is a schematic wiring diagram of an automatic telegraph keying control system embodying features of the invention.

Fig. 2 is a schematic diagram of a modification of the keying arrangement of Fig. 1.

Referring to Fig. 1, the device within the dotted rectangle 1 represents the signal impulse contacts of any well-known form of tape-controlled telegraph transmitter e. g., an automatic Morse sender. The transmitter includes a pair of fixed contacts 2, 3, and associated movable contacts 4 and 5 carried by a grounded swingable arm assembly 6 which is adapted to rock contacts 4 and 5 under control of the perforated tape which is fed through the machine. The contact assembly 1 is usually referred to in the art as an "auto-head." Contact 2 in the circuit as shown in Fig. 1 is the "spacing" contact and contact 3 is the "marking" contact. Contact 2 is connected to the control grid 7 of a five-element vacuum tube 8 which may be a type #42 tube having an electron-emitting cathode 9, a control grid 7, a suppressor grid 10, a shield grid 11 and a plate or anode 12. It will be understood that a grid-controlled tube of a greater or smaller number of electrodes may be used. Preferably, the shield grid 11 is connected directly to the anode causing the tube to have the operating characteristics of a triode, the grid 10 being connected directly to the cathode 9. The control grid 7 is connected to the cathode 9 through

a bias resistor 13 of approximately 100,000 ohms and a bias battery 14. The resistor and battery are so proportioned that when the contacts 2 and 4 are open, the control grid of tube 8 is negatively biased substantially to plate current cut-off.

The marking contact 3 is connected to the control grid 16 of a grid-controlled gaseous discharge tube 17 which for example may be of a type #885 or of the "thyatron" type such that when a predetermined negative or blocking potential is applied to grid 16, the tube is blocked against the flow of plate current, but when the said grid has applied thereto a less negative potential, plate current continues to flow independently of the grid potential until the plate voltage is reduced. When the contacts 3 and 5 are open, grid 16 is negatively biased with respect to cathode 18 by means of battery 14 and resistor 15, the latter being of approximately 100,000 ohms. The plate currents of tubes 8 and 17 are supplied by a battery 20 of approximately 250 volts in series with a resistor 21 of approximately 50,000 ohms.

A resistor 19 of approximately 5000 ohms is connected in the cathode return circuit of tube 17 and is also connected across the input electrodes of a vacuum tube 22 which may be of the triode type. Preferably however, tube 22 is a five-element tube of the type #42 with its control grid 23 connected to the screen grid 24 through a grid current limiting resistor 25 of approximately 10,000 ohms and with the cathode 26 connected directly to the suppressor grid 27. Thus the voltage developed across resistor 19 when tube 17 is unblocked, impresses a positive voltage on grids 23 and 24 causing the plate-cathode impedance of tube 22 to drop whereby an effective cathode return circuit for vacuum tube 28 is completed. Tube 28 may be of any well-known form of twin-triode output amplifier tube such as a type #6A6 comprising two sets of triode elements, one set comprising the electron-emitting cathode 29, control grid 30 and plate 31; the other set comprising cathode 29, control grid 32 and plate 33. The source of waves to be amplified is represented by the numeral 34 and is connected through transformer 35 in balanced relation to the grids 30, 32. The midpoint of the secondary winding of transformer 35 is returned to the cathode 29 through the plate-cathode space of tube 28 as mentioned above. The plate current for tube 28 is supplied by battery 36 which may be of approximately 250 volts and is connected in balanced relation to plates 31, 33, through the midpoint of the primary winding of output transformer 37.

The manner of operation of the system of Fig. 1 is substantially along the following lines. Assume that the cathodes of the various tubes have been heated to their proper operating temperatures by suitable cathode heating current sources (not shown) and that batteries of the proper potentials are provided as above described, and that arm 6 is rocked to close marking contacts 3 and 5. Since the arm 6 is directly connected to ground, at the instant of contact, the grid 16 of tube 17 will be at ground potential. At the same instant plate current cut-off bias is maintained on the grid 1 as above described so that tube 8 is ineffective so long as the marking contacts are closed and the spacing contacts are open. The grid bias of tube 17 having been removed by the closure of contacts 3 and 5, a discharge takes place between its

cathode 18 and its anode (not numbered in either Fig. 1 or Fig. 2) proceeding through resistor 21, battery 20, and returning to cathode via resistor 19. The resultant IR drop across resistor 19 causes grids 23 and 24 to assume a positive potential with respect to cathode 26. Tube 22 therefore becomes conductive to an extent sufficient to complete the cathode return circuit of tube 28 thus causing amplification of the waves from source 34. The output energy of tube 28 is then available at the terminals of transformer 37.

In the above sequence of operation, resistor 25 serves to limit the amount of current drawn by the control grid 23 and thus assists in maintaining the screen grid 24 at a potential sufficiently positive to maintain good conductivity between plate 38 and cathode 26. Consequently, a series of signalling waves will appear in the output transformer 37, the beginning of this series being substantially instantaneously coincident with the closure of contacts 3 and 5. Marking current therefore continues to flow at an amplitude determined by the amplification factor of tube 28 and associated circuit elements. This flow of marking current will continue even though the arm 6 is rocked to open contacts 3 and 5 and prior to the closure of contacts 2 and 4. Thus with both sets of contacts open, tube 17 continues to pass plate current and tube 22 continues to remain conductive to provide the cathode return circuit 28 as above described. When a spacing impulse is received, thus causing contacts 2 and 4 to close, the negative bias is removed from control grid 1 which is connected directly to ground through contacts 2 and 4. Tube 8 immediately passes plate current which flows through resistor 21. The drop across resistor 21 is therefore increased to a point at which insufficient anode potential remains on tube 17 to maintain the discharge. Grid 16 therefore regains control of tube 17. At this instant the voltage drop across resistor 19 collapses and removes the positive bias from the grids 23 and 24. The high internal impedance of tube 22 therefore fails to provide an effective cathode return circuit for tube 28 which thereupon ceases to amplify and thus produces a "space" signal. It will be seen therefore, that the actual signals in transformer 37 will consist of substantially square-topped signals or envelopes of A. C. waves whose wave frequency is determined by source 34 and whose amplitude is determined by tube 28.

Instead of employing a mechanically rockable contact member such as the arm 6 of the "auto-head" 1 to control the vacuum tube 8 and the "thyatron" tube 17, the control may be effected by a source of timing waves connected to the contacts 2 and 3. Such an arrangement is shown in Fig. 2 wherein the parts corresponding to those of Fig. 1 are designated by the same numerals. The contacts 2 and 3 instead of being rendered effective by grounded oscillating arms are rendered effective by a source of timing waves 39 connected through a coupling transformer 40 to the points 2, 3. The remainder of the system of Fig. 2 is identical with that of Fig. 1, the block 41 representing the elements 22 to 38 of Fig. 1. The waves from source 39 are so proportioned in magnitude with respect to the bias battery 14 and resistors 13, 19, that the grids 1 and 16 are energized alternately, positively and negatively. The positive half waves applied to grid 1 for example are of sufficient amplitude to overcome the negative bias, thus

rendering the tube 8 conductive. Likewise the positive half waves applied to grid 16 render the tube 17 conductive and at the same time the negative half waves which are applied to grid 7 effectively cut-off the tube 8 from the circuit. With this arrangement therefore, the alternate effectiveness of the tubes can be controlled at much higher frequencies than is possible with the mechanically rocking contact arm 6. The source 39 may be local to tubes 8 and 17 or it may be located at a remote point. It will be understood of course that the source 39 may generate alternating current waves of sinusoidal form or the source 39 and the transformer 40 may be replaced by any well-known form of square-topped timing waves such as direct current impulses or the like. The wave frequency of the timing source 39 may be in harmonic relation to the frequency of the signalling source 34. If the marking and spacing intervals at the output of the amplifier are required to be symmetrical, then preferably the alternate half cycles of the timing oscillator 39 should likewise be symmetrical.

Various changes and modifications may be made in the enclosed embodiments without departing from the spirit and scope of the invention.

What I claim is:

1. In a keying control arrangement, a grid-controlled vacuum tube, a grid-controlled gas discharge tube, the grid of said vacuum tube and the grid of said discharge tube being connected in substantially balanced relation to opposite sides of the signal input circuit, means normally effective independently of received signals to bias the grids of said tubes substantially to plate current cut-off, means to render only said gas tube conductive in response to one kind of signal impulse, and means to render only said vacuum tube conductive in response to a different kind of signal impulse while simultaneously blocking said gas tube, the blocking of said gas tube being maintained under control of the steady conductivity of said vacuum tube.

2. In a keying control arrangement, a grid-controlled vacuum tube, a grid-controlled gas discharge tube, the grid of said vacuum tube and the grid of said discharge tube being connected in substantially balanced relation to opposite sides of the signal input circuit, means normally effective independently of received signals to bias the grids of said tubes substantially to plate current cut-off, means responsive to marking signals to overcome the cut-off bias on one tube only, and means responsive to spacing signals to overcome the cut-off bias on the other tube only, whereby said tubes respond substantially only to transitions from one kind of signal to the other, and means to maintain the gas tube steadily blocked under control of the steady plate conductivity of said vacuum tube.

3. In a keying control arrangement, a grid-controlled vacuum tube, a grid-controlled gaseous discharge tube, means to render said discharge tube conductive only in response to one character of signal, and means responsive to another character of signal to render said vacuum tube conductive and thereby to block said gas tube, by maintaining the plate potential of the gaseous tube below its discharge-maintaining potential as long as the plate circuit of said vacuum tube is conductive.

4. In a keying control arrangement, a grid-controlled vacuum tube, a grid-controlled gas

discharge tube, said tubes being normally biased to plate current cut-off, means responsive to a marking signal and effective only while said vacuum tube is biased to plate current cut-off to render said gas tube conductive, and means responsive to a spacing signal to render said vacuum tube conductive and thereby to block said gas tube, by steadily maintaining the plate potential of the gas tube below its discharge-sustaining value as long as the plate circuit of said vacuum tube is conductive.

5. In a keying control arrangement, a grid-controlled vacuum tube, a grid-controlled gas tube, means normally biasing the grids of said tubes to plate current cut-off, a pair of marking and spacing control contacts, one of said contacts being connected to the grid of the vacuum tube and the other of said contacts being connected to the grid of the gas tube, means to apply a bias neutralizing potential only to one of said grids in response to a marking signal, means to apply a bias neutralizing potential only to the other of said grids in response to a spacing signal, said vacuum tube being effective while its bias is neutralized to reduce and maintain reduced the plate potential of said gas tube below its discharge-sustaining value to restore control of the said gas tube to its grid only while said vacuum tube grid bias is neutralized.

6. In a keying control arrangement, a grid-controlled vacuum tube, a grid-controlled gas discharge tube, means normally biasing the grids of said tubes negatively to plate current cut-off, a marking contact, a spacing contact, means controlled by a perforated tape or the like to ground the said grids in accordance with marking or spacing signals whereby only one tube becomes conductive for marking and only the other tube becomes conductive for spacing.

7. A keying control arrangement according to claim 6 in which the plate potential for the gas tube is connected in series with a resistor, and the anode-cathode discharge path of said vacuum tube is connected in parallel to said resistor and source.

8. A keying control arrangement according to claim 6 in which said vacuum tube is of the five-element type with the screen grid and plate directly connected and with the suppressor and cathode directly connected.

9. In a keying control arrangement, a grid-controlled gas discharge tube normally biased to plate current cut-off, means responsive to a marking signal to reduce said bias to render said tube conductive, means including a grid-controlled vacuum tube responsive to a spacing signal to block said gas tube and to maintain it blocked as long as the plate circuit of said vacuum tube is steadily conductive, and a grid-controlled amplifier tube controlled by the plate current of said gas tube.

10. In a keying control arrangement, a grid-controlled gas discharge tube, a grid-controlled vacuum tube, means responsive to a marking signal to render said gas tube conductive and thereby to apply a positive bias to the control grid of said vacuum tube, and a grid-controlled amplifier tube whose cathode-grid return circuit includes the anode-cathode discharge path of said vacuum tube.

11. In a keying control arrangement, a grid-controlled gas discharge tube, means to render said tube conductive in response to the initiation of a marking signal and for maintaining it conductive only until the initiation of a spacing sig-

nal, a grid-controlled vacuum tube normally biased to plate current cut-off, means connected in the plate-cathode circuit of said gas tube and responsive to plate current flow to bias the grid of said vacuum tube positively, a grid-controlled amplifier tube having a source of signal waves connected to its input electrodes, the return circuit for said input electrodes including the anode-cathode discharge path of said vacuum tube.

12. A keying control arrangement according to claim 11 in which said vacuum tube is of the five-element type wherein the shield grid and control grid are connected together and the suppressor grid and cathode are connected together.

13. In a keying control arrangement, a grid-controlled gas tube, a grid-controlled vacuum tube, a source of reversible signal potentials con-

nected to said grids in substantially balanced relation, the said grids being normally biased to plate current cut-off in the absence of said signal potentials, and an impedance common to the 5 plate circuits of said tubes and responsive to the steady conductivity of said vacuum tube whereby when the vacuum tube becomes conductive, it causes said gas tube to become non-conductive.

14. A keying control arrangement according to 10 claim 13 in which another impedance is connected in the anode-cathode circuit of the gas tube and a second grid-controlled vacuum tube is connected across said other impedance whereby the control grid of said other vacuum tube is 15 positively biased only when said gas tube is conductive.

RICHARD A. HILFERTY.
